UNITED STATES PATENT OFFICE.

EZRA JACOB ZOLLINGER, OF LOGAN, UTAH.

CARBURETOR.

Application filed July 28, 1925. Serial No. 46,632.

This invention relates to an improved carburetor and seeks, among other objects, to provide a device of this character wherein vaporization of the liquid fuel will, as compared with existing devices, be more effectively accomplished, wherein the fuel mixture will be rendered more combustible so that maximum energy will be realized from the quantity of fuel used, and wherein economy will be effected in the use of the fuel.

The invention seeks, as a further object, to provide a device wherein the liquid fuel will be heated prior to the vaporization thereof by a stream of hot air subsequently mingled with the fuel to form a crude heated vapor, and wherein the crude vapor will then be diluted and cooled by a proportionate quantity of fresh auxiliary air to form a cool highly combustible fuel mixture.

The invention seeks, as a further object, to provide a device wherein the quantity of fresh air admitted will be automatically controlled and will be gradually increased with the speed of the engine to which the device is attached for thus effecting a saving in the consumption of fuel and maintaining the fuel mixture at the proper temperature.

And the invention seeks, as a still further object, to so construct the device that the parts may be readily and economically formed and assembled.

Other objects of the invention not above specifically mentioned will appear as the description proceeds.

In the accompanying drawings:

Figure 1 is a vertical longitudinal sectional view through my improved carburetor.

Figure 2 is a horizontal sectional view on the line 2-2 of Figure 1, looking in the direction indicated by the arrows.

Figure 3 is a vertical detail sectional view taken through the fuel nozzle at right angles to the section of Figure 1.

Figure 4 is a fragmentary elevation showing the auxiliary air port and the fuel vapor port of the mixing chamber of the device.

In carrying the invention into effect, I employ a cylindrical mixing chamber 10 having a bottom wall 11 extended to form an eccentrically disposed circular flange 12, and depending from said bottom wall is a stem 13 having a diametric passage 14 and an axial passage 15 leading downwardly therefrom and provided below the former passage with a shoulder 16. Formed in the rear side of the chamber 10 near its lower

end are like triangular auxiliary air ports 17 midway between which is provided an elongated tapered fuel vapor port 18 extending at its lower smaller end below the lower smaller ends of the ports 17, and extending from the opposite side of said chamber opposite said ports is a fuel mixture outlet 19 flanged for attachment to an intake manifold indicated at 20. The outlet carries a throttle valve 21, and rising from said outlet is a web 22 provided with a suction passage having angularly disposed communicating portions 23 and 24 connecting the base end of said outlet with the upper end of the mixing chamber 10. Screwed through said web to project across the upper end of the portion 23 of the passage into the portion 24, is a needle valve 25 adjustable for partially closing said passage. Near its lower end, the chamber 10 is provided with an internal annular ledge 26 disposed below the lower ends of the ports 17, and extending through the adjacent side of said ledge at the lower end of the port 18 is a passage 27 while, at its opposite side, said ledge is provided with a like passage 28 communicating with the outlet 19. Slidably fitting in the mixing chamber is a hollow piston valve 29 which is open at its lower end and closed at its upper end and normally rests upon the ledge 26 extending over the ports 17 and 18 as well as the outlet 19. Closing the chamber 10 at its upper end is a removable cover plate 30. Fitting the side wall of the chamber 10 to overlie the port 18 is an elbow-shaped fuel vapor conduit 31, and straddling said conduit is a mating auxiliary air inlet 32 also fitting the wall of said chamber to overlie the ports 17. The conduit and said inlet are both detachably secured to the said wall of the chamber and mounted in the inlet is an auxiliary air valve 33.

Mating with the flange 12 at the bottom of the chamber 10 is a fuel bowl 34, the bottom wall of which is apertured to fit the stem 13, abutting the shoulder 16, and formed on the bowl is a nipple 35 to which is attached a liquid fuel supply pipe 36. Pivottally mounted within the bowl is a valve lever 37 which is operated by a float 38 and carries a needle valve 39 controlling the admission of fuel to the bowl. Connected to said stem is a cruciform fitting 40 having a primary air inlet 41 opposite which is a communicating Venturi tube 42, and lying at a

right angle to said inlet and tube is a liquid fuel conduit 43 opposite which is an alined nipple 44 connected with said conduit by a tubular bridge member 45 extending across the passage of the inlet 41 at the junction of said inlet with the tube 42. The tube 42 fits in the lower end of the conduit 31 and is secured by a set screw 46, while the conduit 43 is provided with a sleeve 47 which fits over the stem 13 and is secured by a nut 48 screwed on the lower end of said stem, the bowl 34 being also thereby clamped in position. The conduit 43 has a passage 49 which, at one end, communicates with a passage 50 through the bridge member 45 while, at its opposite end, the passage 49 enters the sleeve 47 to communicate with the passage 15 of the stem, and screwed into the nipple 44 is a needle valve 51 adjustable for regulating flow through said passages. Connected to the inlet 41 is a pipe 52 for supplying heated primary air to said inlet, and mounted in the inlet is a primary air inlet valve 53. Screwed at its lower end into the bridge member 45 to communicate with the passage 50 thereof is a liquid fuel nozzle 54 which extends axially of the Venturi tube 42 and terminates at its upper end in the throat of said tube above the level of the fuel in the bowl 34.

As will now be seen, when the engine is started, engine suction will be communicated through the passages 27 and 28 to the conduit 31 so that heated primary air will be drawn through the pipe 52 and inlet 41 around the bridge member 45 and upwardly through the tube 42 past the nozzle 54. The bridge member and nozzle will thus be heated by the currents of heated air so that the fuel flowing from the bowl 34 through the passages, 14, 15, 49 and 50 into the nozzle will, in turn, be heated by said bridge member and the nozzle. Heated liquid fuel will thus be aspirated by the current of heated air into the conduit 31 whereupon the atomized fuel and air will mix to form a crude fuel vapor flowing through the passages 27 and 28 and through the outlet 19 to the engine. Coincident with the starting of the engine, engine suction will be communicated through the portions 23 and 24 of the suction passage to the chamber 10 above the valve 29 with the result that said valve will be lifted to partially uncover the ports 17 and the outlet 19 so that fresh air will be drawn in through the inlet 32 into the mixing chamber beneath the valve to mix with the fuel vapor and form a cooled highly combustible fuel mixture. The valve 25 is provided to regulate the suction through the portions 23 and 24 of the suction passage in order that, as the engine is accelerated, the valve 29 will be gradually lifted, and attention is now directed to the fact that, as the valve is lifted to permit an increased flow of fuel

vapor through the port 18, the volume of fresh air admitted will, due to the greater combined areas of the ports 17, be increased faster than the increase in volume of the fuel vapor. Accordingly, as the engine is accelerated and engine suction is increased, a gradually increasing quantity of fresh auxiliary air will be admitted to form a properly diluted fuel mixture correctly cooled to avoid premature expansion. When running at low speeds, the ports 17 are nearly closed, and when the engine is idling, said ports will be completely closed, in which event all the suction is exerted through the main air inlet 41 and the nozzle 54. All the admitted air will then be heated and while playing upon the bridge 45 and nozzle 54 will tend to vaporize the fuel which could not occur if the air were cold. Of course, the air will not be heated in originally starting the engine but this condition is met by properly regulating the choker valves 33 and 53.

Having thus described the invention, what I claim is:

1. A carburetor including a mixing chamber provided in its wall with a fuel inlet port and an auxiliary air inlet port as well as a fuel mixture outlet, a suction operated valve slidable in said chamber and normally closing said air inlet port and extending across the fuel inlet port and said outlet, a mixture conduit attached to the wall of said chamber and overlying said fuel inlet port, a liquid fuel nozzle, means for conducting liquid fuel to the nozzle, and a separate fitting mounting said nozzle and connected to said conduit, said fitting being provided with a primary hot air inlet supplying a current of hot air heating the liquid fuel prior to entrance thereof into the nozzle and flowing about the nozzle for aspirating the fuel therefrom and supplying a heated fuel to said conduit.

2. A carburetor including a mixing chamber provided in its wall with a fuel inlet port and an auxiliary air inlet port as well as a fuel mixture outlet, a suction operated valve slidable in said chamber and normally extending across said outlet as well as said ports, a mixture conduit attached to the wall of said chamber and overlying said port, an auxiliary air inlet straddling said conduit and attached to the wall of said chamber to overlie said air port, a liquid fuel nozzle, means for conducting liquid fuel to the nozzle, and a separate fitting mounting said nozzle and connected to said conduit, said fitting being provided with a primary hot air inlet supplying a current of hot air heating the liquid fuel prior to entrance thereof into the nozzle and flowing about the nozzle for aspirating the fuel therefrom and supplying a heated fuel to said conduit.

3. A carburetor including a mixing cham-

ber provided with a stem, a liquid fuel bowl surrounding the stem, a separate fitting attached to the stem and provided with a Venturi tube communicating with the mixing chamber, the fitting being provided with a primary hot air inlet communicating with said tube and being formed with a bridge member extending across said hot air inlet and receiving liquid fuel from the bowl 5 through said stem and fitting, and a nozzle mounted upon said bridge member to up- stand within said tube, said primary hot air inlet supplying a current of hot air heating said bridge member and flowing about the 10 nozzle for aspirating the fuel therefrom and supplying a heated fuel mixture to the mixing chamber.

4. A carburetor including a mixing chamber, a stem depending from the mixing 15 chamber and having a fuel passage there-

through and provided with an external shoulder, a liquid fuel bowl abutting the bottom of the mixing chamber and said shoulder, a fitting mounted on the stem against the bowl, the fitting having a fuel passage 25 communicating with the fuel passage in the stem, means for securing the fitting on the stem against the bowl and clamping the bowl against said shoulder and the mixing chamber, a Venturi tube rising from the fitting and communicating with the mixing chamber, a hot air inlet on the fitting alined with the tube, a hollow bridge within the fitting extending across said hot air inlet and receiving liquid fuel through the fitting, a 30 valve in said bridge for controlling the flow of fuel, and a nozzle rising from said bridge within the tube.

In testimony whereof I affix my signature.
EZRA JACOB ZOLLINGER. [L.S.]
